United States Patent Office.

T. J. BURKE, OF SANDWICH, ILLINOIS.

Letters Patent No. 90,339, dated May 25, 1869.

IMPROVED BRICK-PRESS.

The Schedule referred to in these Letters Patent and making part of the same

To all whom it may concern:

Be it known that I, T. J. BURKE, of Sandwich, in the county of De Kalb, and State of Illinois, have invented certain new and useful Improvements in Hand Brick-Machines; and I do hereby declare that the following is a full, clear, and exact description thereof, reference being had to the accompanying drawings, and to the letters of reference marked thereon, which form a part of this specification, and in which—

Figure 1 represents a perspective view,

Figure 2, a side view of the plunger, and

Figure 3, a top view of the plunger.

Similar letters indicate like parts in all the figures.

My invention relates to improvements in brick presses; and to this end consists in the employment of a plunger, operated by means of a pivoted lever, in combination with such other devices as will be hereinafter fully set forth.

To enable others skilled in the art to which my invention appertains, to make and use the same, I will now describe its construction and operation.

In the accompanying drawings—

A represents a frame, consisting of the side-pieces $a a$, which may be secured together by means of iron rods, and are provided, between their upper ends, with a mould or receptacle, b , for the brick.

$b' b'$ are slots made in the side-pieces, the object of which will be hereinafter described.

$a' a'$ are plates attached to the sides of the mould, for the purpose of attaching the press to the table or bench.

c is a wire frame, secured to the front side of the mould, as seen in fig. 1.

B represents the plunger, provided at its upper end with the plunging-plate c' .

The sides of the plunger are secured together by

the roller d , the ends of which pass through the slots $b' b'$ in the side-pieces $a a$, and which is attached at each end, outside the side-pieces, to the lower end of the pivoted frame $e e$.

D is a roller, pivoted between the upper ends of the pivoted frame $e e$.

This roller is provided with projections $e' e'$, into which is pivoted the cap E by means of the projections $f f$ on the cap and the rod f' .

F is a lever, attached to the roller D.

The operation of my machine is as follows:

The press is first secured in a vertical position to any suitable table or bench by the plates $a' a'$, and the brick, after being dried, are placed in the mould b ; then, by operating the lever F, the pitmen $e e$ force the plate on the plunger B against the brick in the mould b , and the cap E, covering the upper part of the mould, forms a complete press for the brick.

Having thus described my invention,

What I claim as new, and desire to secure by Letters Patent, is—

1. The combination, substantially as set forth, of the pivoted frame $e e$ and plunger B, connected together and retained in their respective places by means of the slots $b' b'$ in the side-pieces $a a$, as described.

2. The press, consisting of the frame A, provided with side-pieces $a a$ and slots $b' b'$, pivoted frame $e e$, mould b , roller D, cap E, lever F, and plunger B, all combined, arranged, and operating substantially in the manner and for the purpose described.

In testimony that I claim the foregoing as my own, I affix my signature, in presence of two witnesses.

T. J. BURKE.

Witnesses:

HERON POTTER,
LUTHER HILLS.
